AIR COOLING APPARATUS

Kenneth E. Whitlock, Detroit, Mich., assignor, by
mesne assignments, to Refrigerated Air Conditioning
Corporation, a proposed corporation
of Michigan

Application April 8, 1937, Serial No. 135,767

2 Claims. (Cl. 62—129)

This invention relates to a device for cooling air, and it has to do especially with a device more or less of a portable nature which can be purchased upon the market, placed in the room of an office or home, electrically connected to the wiring system and operated to cool the ambient atmosphere.

Air conditioning systems have been proposed, and such systems usually embody a structure more or less built into a building permanently, and having, for example, air conditioning mechanism located in the basement and air ducts leading therefrom to the various rooms of the building. Such mechanism is expensive and entails considerable work at the time of installation. It is believed that the accepted definition of the term "air conditioning" means an apparatus which will not only temper the air as by cooling, but which also humidifies the air and cleans the same. The invention, however, in its present form aims only to cool the air, and such humidifying or dehumidifying of the air and cleaning which may occur in its operation, in the form of device shown in the accompanying drawings, may be considered as incidental. The cooling apparatus may, however, be used in conjunction with humidifying and cleaning means.

The general objects of the invention are to provide an apparatus which may be compactly assembled in a cabinet and merely brought into a room, electrically connected with the wiring system, and set into operation. No installation work is necessary. A further object is the provision of a device which may be cheaply manufactured and offered to the public at a low cost, and which, by reason of its construction, has an improved operating efficiency. In considering the efficiency due regard must be given to the volume of air which passes through the device and the degree to which the air is cooled. The device of the present invention has a high efficiency in both of these factors.

One concrete example of a device for carrying out the invention is shown in the accompanying drawings, wherein:

Fig. 1 is a perspective view illustrating a cabinet with the structure therein and located in the corner of a room.

Fig. 2 is an enlarged cross sectional view taken substantially on line 2—2 through an air exhaust conduit which may be used.

Fig. 3 is an enlarged sectional view taken substantially on line 3—3 of Figs. 1 and 5.

Fig. 4 is a perspective view with portions cut

away and some portions in section looking into the cabinet.

Fig. 5 is an enlarged view partly in section taken substantially on line 5—5 of Fig. 4.

Fig. 6 is a sectional view taken substantially on line 6—6 of Fig. 5.

The mechanism may be mounted in a cabinet 1 of any suitable design and the mechanism takes the form of a mechanical cooling apparatus which embodies a refrigerating medium. The compressed refrigerant is condensed by an air cooled unit and the heated air is discharged through a conduit 2 which preferably leads outside the room. The conduit may be of a fabric tubular structure 3 with a helical coil 4 of metal 15 therein so that the structure may be lengthened and shortened within certain limits with an accordion action. The cabinet is provided with a tubular outlet extension 5 to which one end of the conduit may be secured as by means of a clamp 20 6, and the other end may be secured to a tubular sleeve 7 as by means of a clamp 8. The tubular sleeve 7 may be mounted by the means of a gasket 9 to a panel 10. This panel 10 is preferably associated with another panel 11, the panels being 25 slidable relative to each other for fitting windows of various widths. When the panels are placed in the window opening, the window frame, as illustrated at 12, may be lowered upon the top of the panels to close the opening.

As illustrated in Fig. 5 the cabinet has an outlet opening for cool air preferably equipped with a suitable grill 15 and an inlet on its back side preferably covered by a screen or grill 16. The cabinet may have a considerable part of its back wall 35 35 of screen or grill structure as illustrated at 17, this grill structure being of such extent as to permit air to pass over some operating mechanism as will presently appear. The cabinet may have another grilled opening as at 18, although 40 this is optional.

Mounted in the cabinet in a substantially centralized position is a motor 20, the shaft of which is illustrated at 21, and which projects from both sides of the motor housing. A so-called blower 45 type of fan is mounted upon each end of the shaft. This blower type of fan is generally called a Sirocco fan and is of the centrifugal type, in that air enters axially, and is forced out in a radial direction. These fans are preferably of 50 double construction. One fan, as illustrated at 22, has fan blades on both sides of an intermediate partition 23. The other fan 24 has blades or a fan portion on both sides of an intermediate partition 25.

- The cooling mechanism comprises a condenser 26 operated by a belt 27 running over pulleys on the motor shaft and the compressor shaft. The outlet conduit for compressed refrigerant is illustrated at 28 and it leads to a condenser 29 here shown as made up of a plurality of runs or coils of finned tubing. From the compressor the refrigerant passes through a conduit 30 to a receiver tank 31 and then through a suitable strainer 32. From the strainer 32 refrigerant passes through a conduit 33 to a control device 34 which may be a chamber containing a float valve for controlling the flow of refrigerant into a pipe line 35 leading to an evaporating unit or cooling unit 36. This cooling unit is here shown as comprising a plurality of runs or coils of finned tubing. From the evaporator the refrigerant runs through a pipe line 37 to the compressor.
- It will be understood by those skilled in the refrigeration art that a suitable amount of refrigerant is contained in this system and it is passed in a circuitous path wherein it is compressed by the compressor 26, condensed into liquid form by the condenser 29, is passed to the evaporator 36 in a controlled manner by the float valve 34 or other control, where the refrigerant evaporates and extracts heat from the air surrounding the same, and then in gaseous form is returned to the compressor to be again compressed. This entire structure is driven by the motor as are also the Sirocco fans.
- The cabinet is equipped with a passageway extending substantially from the air inlet 16 to the outlet 15. This may be in the nature of a sheet metal flue 40 in which the evaporator, or at least the major portion thereof, is located. At the location of the fan 22 the walls of the passageway are formed outwardly as illustrated at 41 and 42. The fan is surrounded by a casting or housing 43 (Fig. 3) and the outward formation of the walls 40 permits the air to divide into two streams and enter the fan from opposite sides as illustrated by the arrows in Fig. 5. The shell 43 is open at the side of the fan adjacent the outlet 15 so that the air is blown outwardly by the fan. Suitable insulation 44 and 45 may be used around the unit which cools the air.
- The fan 24 is likewise partially surrounded by a shell 50 (Fig. 6) and the condenser unit 29 may be located in a passageway provided by walls of sheet metal or the like as illustrated at 51. The walls 51 terminate short of the axis of the fan as illustrated in Fig. 6, and in cooperation with the shell 50, provide air passageways 52 for the entrance of air into the fan from opposite sides thereof. The fan 24 forces air across the condenser and through the conduit 2 which may lead to the outside of the room, either outside the building or elsewhere. The replacing air may enter through the grill work 17 at the rear of the cabinet and some through the grill 18. Some of this air passes over the condenser and motor as illustrated. This air is air at room temperature and in passing over the condenser and motor serves to cool the same. The heating of the air in this manner does not interfere with the operation of the unit, as this air is discharged through the conduit 2.
- In the operation of the device the evaporator 36 is cooled and the fan 32 draws air across the evaporator, in which action this air is cooled and discharged into the room. At the same time the heated compressed refrigerant is condensed

because the fan 24 causes a flow of air across the same, which air, being heated by this action, is discharged through the outlet conduit. The supply of air which the fan 24 draws upon, or at least some of the supply of air, serves also to cool the condenser and motor and this air is used for this purpose before it has been further heated by the condenser 29.

It has been found that a structure built in accordance with this disclosure is particularly efficient and has a greater volume and more cooling capacity than a number of other units which have been comparatively tested. The arrangement of the fans is a factor aiding in this efficiency, as fans of this type are effective for producing a considerable volume in the flow of air. The centralized location of the motor and other mechanism facilitates assembly and structure, balances the weight in the cabinet and provides an expedient arrangement for a single motor to drive the two fans and compressor. The presence of the two fans gives a balancing action on the motor bearings.

Now it will be observed that the exhaust air fan 24 is somewhat larger than the cold air fan 22. The passageway 51 may be larger than passageway 40. This increases the efficiency of the machine since the exhaust fan has a greater capacity than the cold air fan. In one example which may be cited, the exhaust fan had a diameter of 6 $\frac{3}{8}$ " giving it a capacity of 740 cubic feet per minute at 1725 R. P. M.; whereas the cold air fan had a diameter of 4 $\frac{3}{4}$ " with a capacity of 490 cubic feet per minute at 1725 R. P. M. It may be difficult to explain just why this feature aids in the efficiency of the machine, but it appears that by this arrangement the exhaust fan tends to exhaust more air than the cold air fan tends to discharge, with the result that there is no back pressure or back load on the cold air fan. This is, of course, a matter of theory subject to change, and other theories may be advanced without, however, escaping from the scope of the invention. Due to the fact that the exhaust tube can be extended or shortened within certain limits some flexibility is provided for the location of the unit in a room.

I claim:

1. An air cooling and ventilating apparatus comprising in combination, a cabinet, a motor having a shaft and positioned substantially centrally of the cabinet, an air passageway adjacent one end of the cabinet having an inlet at the back of the cabinet and an outlet at the front, refrigerating mechanism including a compressor positioned substantially centrally of the cabinet, means operating the compressor from the shaft, an evaporator positioned in said passageway, a condenser positioned adjacent the other end of the cabinet, a second passageway around the condenser and positioned adjacent said opposite end of the cabinet and having an open end adjacent the front of the cabinet and extending out of the cabinet, said cabinet having air inlet means, some of which are located in the back wall so that air may pass therethrough over the condenser and motor and into the open end of the second mentioned passageway, the shaft of said motor projecting to opposite sides thereof, and a double blower type fan on each end of the shaft, one for moving a current of air over the evaporator in the first mentioned passageway and for discharging said air into a room and the other for moving a current of air through the second

mentioned passageway for discharge of the air outside said room.

2. An air cooling and ventilating apparatus for a room comprising in combination, a cabinet, 5 partition walls defining a passageway adjacent one end of the cabinet, said passageway having an air inlet adjacent the front of the cabinet and an outlet extending through the back of the cabinet and adapted to extend outside the room, the cabinet having walls formed for the passage of room air into the same and into the said inlet for the passageway, partition walls adjacent the opposite end of the cabinet having an air inlet through the back wall of the cabinet and an air outlet through the front wall of the cabinet, refrigerating mechanism including a compressor located in the intermediate part of the cabinet

between the two passageways, a condenser in the first mentioned passageway and an evaporator in the second mentioned passageway, an electric motor positioned in the intermediate zone of the cabinet between the two passageways adjacent one outside wall of the cabinet and adjacent the compressor, a shaft extending through the motor and having its ends projecting into the two passageways, a blower fan on each end of the shaft, one located in one passageway and one located 10 in the other for exhausting room air through the first mentioned passageway and for circulating room air through the second mentioned passageway, and means operatively connecting the motor to the compressor for operating the same. 15
